UNITED STATES PATENT OFFICE.

FREDERICK D. SCHNEIDER, OF ELIZABETH, NEW JERSEY, ASSIGNOR TO THE LONG-
LANDRETH-SCHNEIDER COMPANY, OF NEW BRUNSWICK, NEW JERSEY.

STORAGE-WATER HEATER.

1,317,039.

Specification of Letters Patent. Patented Sept. 23, 1919.

Original application filed September 9, 1915, Serial No. 49,762. Divided and this application filed August 25, 1916. Serial No. 116,799.

To all whom it may concern:

Be it known that I, FREDERICK D. SCHNEIDER, a citizen of the United States, residing at Elizabeth, in the county of Union 5 and State of New Jersey, have invented a new and useful Improvement in Storage-Water Heaters, of which the following is a specification, the principle of the invention being herein explained and the 10 best mode in which I have contemplated applying that principle, so as to distinguish it from other inventions.

My alleged invention relates to a water heater and more particularly to apparatus 15 combining all the advantages of the automatic type with all the advantages of the storage type. Such specific principle is shown, described and claimed in United States Letters Patent No. 1,232,435, issued 20 July 3rd, 1917, to The Long-Landreth-Schneider Company as my assignee. The disclosure of this application constitutes a 25 modification in respect to the shape, arrangement, proportion and function of various essential parts.

I know that instantaneous automatically operated heaters have been combined with a storage supply, but believe, as the existence of the above identified earlier application 30 attests, that the relationship there explained and here incorporated is new as well as useful. The gist of that idea is to so alter the value of a certain ratio between the capacity to heat instantaneously and the 35 storage supply as to successfully achieve the service of either or both of the two types heretofore required; and to do this with a structure operating as a unit with greater efficiency. The water heater to be now de- 40 scribed is a circulating tank heater or circulating boiler heater wherein all the hot water is delivered from the tank or boiler supply.

The distinct and separable objects of the 45 present invention are now enumerated. In general, I aim to manufacture a safe, durable and efficient heater in a simple, compact, neat, feasible and economical manner. Specifically, I mount the tank directly above and in line with the center line; contrive to have a separated reverse flow through a single connection; require less metal for the coil both because of a comparatively smaller bore and reduced length thereof, such re-

duced length being sufficient because the 55 stream passing through is less and because the style of coil absorbs more heat; employ a plural wound conical coil unit; make the lower border of the latter conform to and touch the jacket; and locate the burner orifices inside of the inner confines of the coil bottom.

To more clearly instance the distinctions which this application is known to present over previously marketed storage water heaters, mention is made of the three types of what may be termed combination storage water heaters which have heretofore been marketed.

a. A storage tank is separately supported 70 and a heater likewise at the side thereof. This style of apparatus occupies too much space, was not balanced and inadequately efficient because the heater is not directly below the tank.

b. Both heating conduit and burner being within the confines of the tank. This arrangement is unsafe because the apparatus as a whole cannot be opened in order to disperse any gas that might have accumulated, 80 preparatory to lighting. Safety is not assured unless a door opening from top to bottom is provided. Furthermore, non-accessibility mitigates against its usefulness. Also, when no heat is being supplied, a cold 85 draft passes through the vent necessitated through the center of the tank. Why insulate outside if the inside is to be exposed to a cold draft.

c. An absence of a water conduit features. 90 A tank is fashioned with a flue through its center in which a spiral baffle is set. This expedient does not heat rapidly enough. Moreover, it is equally inaccessible, and its inclosed burner similarly involves danger 95 when lighting. Such water as is touching the central flue when the heat is no longer being applied starts to cool and consequently such of it as is above owing to its greater weight will settle and hence cause a circulation.

The heater embodying the present invention:

Has its heater separate from the confines 100 of the tank.

Has no flue passing through its middle.

Has its entire exterior excepting the bottom insulated.

- Has its tank directly supported by the heater by means of a featured connection.
Has a conical coil of single or plural winding.
5 Has a central by-pass connection between the top and bottom.
The whole is of rigid construction efficient in operation and besides, quite free from troublesome condensation. Only by properly proportioning the size of the by-pass and the bore of the coil is it possible to achieve perfect results. The by-pass serves to regulate the temperature of the water, which should not become overheated to lime the 10 coils. If the friction of the water rising through the coil is excessive the overheating can likewise occur. The pitch of the convolutions of the coil should be taken into consideration. Any one of these factors being known, one or more of the rest should be modified accordingly if the best average utility is to be had.
I would have it expressly understood that I in no wise limit myself to these specific 15 applications or embodiments of my invention, which I have selected as a basis for illustrating and describing my invention merely for the purpose of rendering a clear and comprehensive understanding of the 20 scope and novel features thereof.
- Adverting to the drawings:
Figure I is a mainly vertical section of a water heater embodying my invention.
Fig. II is an enlarged section of a portion 25 of one part shown in Fig. I.
Fig. III is a similar section showing a modification in certain respects.
Fig. IV is a horizontal section on line 4-4 of Fig. III.
40 As appears in Fig. I the entire construction is supported upon a single pedestal 1 the upper extremity being screw threaded at 2 for coöperation with the complementary screw threads of a hollow fitting 3. This 45 latter is additionally provided with a screw threaded inlet 4 and a duplex outlet 5. Fitted in the opening 4 and extending upwardly in line with the pedestal is a pipe 6 which carries on its upper end a hollow 50 casting 7 of peculiar formation to comprise a pair of ducts 8 and 9 the latter of which passes through the former. No direct communication is afforded between the ducts 8 and 9. The duct 8 communicates below 55 with the pipe 6 and in practice accommodates the passage of the cooler water. The duct 9 terminates below in a laterally directed inlet opening 10 and extends upwardly a considerable distance beyond the 60 upper extremity of the duct 8. The duct 9 is adapted for the upward travel of the water which has the greatest temperature, as will later become apparent, and as is likewise indicated by the arrows. Just above 65 the lower inlet 10 of the duct 9 but below

the upper extremity of the duct 8 the latter carries a cylindrical jacket 11 of any suitable construction and dimension. Such jacket will be provided in front with a door and at another point with a stack outlet, 70 neither of which is shown.

A union 12 effects a detachable connection with a short pipe 13 which is screw threaded or otherwise secured in a flanged collar 14 upon which a storage tank 15 is supported. 75 It will be noticed that the duct 8 has free communication with the bottom of the tank through the collar 14 and around the duct 9 which extends to within a short distance of the top of the tank 15. The tank 15 is covered around its sides and above with any approved insulation 16. A cold water inlet pipe 17 and a hot water outlet pipe 18 appear connected with the top of the tank. 80

Projected through one side of the tank 85 bottom is a sensitive thermostatic tube 19 which is adapted to actuate the snap-acting mechanism of a thermostat 20. Such thermostatic mechanism is adapted in turn to operate a gas valve not shown but purposed 90 to control the flow of fuel to the connection 21 leading to a burner 22 having removable burner heads 23 positioned near the bottom of the jacket 11 and embodying the principles of United States Letters Patent No. 95 1,241,032 issued September 25, 1917, to The Long-Landreth-Schneider Company as my assignee. The dimensions of the burner 22 are preferably such as to be smaller by a predetermined measure than the diameter of the jacket as will be more particularly explained later. A small pipe 24 is connected with the source of gas ahead of the thermostatically controlled valve in order to constantly supply fuel to the pilot 25. 100

A plural wound, in this instance duplex, copper coil 26 has its one pair of end openings 27 in braised connection below with the outlet 5 and its other upper pair of end openings 28 in similar connection above with the inlet 10. The coil 26 is of conical form and according to my invention has its lowermost duplex convolution abutting the interior of the jacket 11 as shown for example at 29 and 30. The shape, arrangement and proportion of the coil 26 in its relation to the burner heads 23 and the jacket 11 and with respect to the capacity of the tank 15 is such as to permit of employing copper tubing of not only less length but smaller 110 size of bore and in so far constitutes one of the features of my present invention. The applicant has discovered that by positioning a conical coil like the one shown and described, or its equivalent, with reference 115 to the casing as described and as otherwise connected, that a given rate of flow of water may be heated to a predetermined desired temperature with a comparatively smaller and hence more economical heating unit. 120

These coils are commonly made of copper which is, of course, an expensive metal, so that if its bore and length can be reduced and yet heat a given rate of flow of water 5 a meritorious invention appears to have been achieved. The ratio between the length of the coil and the diameter of its bore is substantially as four hundred and three and two-tenths is to one. I purposely arranged 10 the burner heads 23 not only an advisable distance below the bottom of the coil 26 but also nearer the center of the coil than the inner surface of the lowermost convolution. By so doing I avoid the objectionable direct 15 impinging of a flame against the nearest section of the coil.

In operation, as the water is heated in the coil it rises therethrough along a sinuous course to emerge from the openings 28 and 20 pass up through the duct 9 into the upper confines of the tank. The coolest water in the meantime seeks its true level and accordingly flows down through the duct 8 to pipe 6 and passes into the coil through the opening 25 ing 27.

A decided advantage ensues in having the hot water duct 9 within the duct 8 owing to the fact that the cooler water passing downwardly around the duct 9 serves as 30 an effectual insulation therefor. Also, my manner of connecting the tank and heater is not only simple, but very quick of accomplishment. The size and disposition of my burner with respect to the bottom of the coil 35 insures a nearly uniform licking of the interior surfaces of the progressively smaller convolutions and avoids the conveyance of undue heat likely to burn the lowermost convolution.

40 The modification disclosed in Figs. III, IV and V consists in the provision principally of a plurality of separate conical coils either single or plural wound, each of which is separately supported upon a base, and 45 all of which are uniformly spaced with reference to the axis of the heater as a whole, and furthermore, surrounded by a jacket which is a continuation of the insulation enveloping the tank. Specifically, a base 50 32 is fashioned with a quartet of bosses 33 having screw threaded unions in which a corresponding number of supports 34 are secured. Each of the latter carries a hollow fitting 35 from which a pipe 36 continues 55 upwardly to communicate with a hollow

casting 37 which incloses a distinct duct 38 extending upwardly into a tank 39. A conical coil 40 is connected below with the fitting 35 and above with the duct 38 while a burner construction 41 having burner heads 60 42 arranged as shown is provided below. The insulating composition 43, the size of which is determined by the dimensions of the tank is continued below the bottom of the latter and is thus adapted to serve as a 65 jacket or heat confining agency for the plurality of coils.

I claim:—

1. A water heater of the class described comprising, a pedestal, a hollow structure extending upwardly therefrom, a tank supported by said structure and communicating at separated points therewith, a casing also carried by said structure, a conical heating coil communicating at different points with said structure and having its lower end closely fitting to the interior wall of said casing, and a burner below said coil. 70 75

2. A water heater of the class described comprising, a pedestal, a hollow fitting carried thereby and provided with a pair of openings, a pipe fitted in one of said openings, a hollow casting in communication with the upper end of said pipe and provided with three additional openings, a heating coil having its ends communicating with the other opening of said hollow fitting and with one of said casting openings respectively, a tank carried by said casting and in communication with its two other openings, 80 85 a burner below said coil and a casing inclosing said coil and burner.

3. A water heater of the class described comprising, a pedestal carrying a hollow structure provided with a baffle, a heating coil about said structure and baffle and having one of its ends in communication with said structure, a casting formed with a pair of concentric pipes having separated openings in communication with the other end of said coil and with said structure respectively, a tank detachably connected with said casting and in communication with the other ends of said pipes, a burner below 95 100 said coil, and a casing also carried by said casting and inclosing said coil.

Signed by me, this 7th day of August, 1916.

FREDERICK D. SCHNEIDER.
